UNITED STATES PATENT OFFICE.

WILLIAM D. SNOWMAN, OF ASHLAND, MAINE.

TOOL-HANDLE REMOVER.

Application filed September 21, 1921. Serial No. 502,159.

To all whom it may concern:

Be it known that I, WILLIAM D. SNOWMAN, a citizen of the United States, residing at Ashland, in the county of Aroostook and State of Maine, have invented certain new and useful Improvements in a Tool-Handle Remover, of which the following is a specification.

This invention relates to tool handle removers and more particularly to a novel and improved device for removing the broken or split handles from axes, hammers, and like types of tools.

The primary object of the invention is to produce a strong and rigid structure having a false bottom, including provision for securely clamping the head of a tool in position so that the end of the handle may be exposed to receive a blow with a striking pin, whereby the said handle may be easily removed from the head of the tool and replaced by a perfect handle.

Another object of the invention is to produce a device of the class above set forth, capable of use for removing the handles from various types of tools, including provision for clamping a striking pin holder positioned above a tool head and the end of a handle, whereby a downwardly directed blow on a striking pin may be imparted to the end of a broken or split handle and remove the same from the head of the tool.

Another and very important object of the invention is the provision of a tool handle remover of the class above set forth, which is extremely simple in construction, easily assembled, rigid and durable, highly efficient in operation, practical and capable of being manufactured of different materials at a very low cost, whereby its commercial possibilities are greatly enhanced.

With these and other objects in view, the invention consists in certain novel features of construction as hereinafter shown and described and then specifically pointed out in the claims, and in the drawings illustrative of the preferred embodiment of the invention:—

Figure 1 is a side view of the invention showing a tool head in dotted line position therein,

Fig. 2 is an end elevation with the tool head in section,

Fig. 3 is a plan view,

Fig. 4 is a detached perspective view of the striking pin,

Fig. 5 is an end elevation of a modified construction,

Fig. 6 is a detached perspective view of one of the side members of the modified structure shown in Fig. 5,

Fig. 7 is a detached perspective view of one of the detachable tool head supports.

Like parts are designated by corresponding reference characters throughout the several views.

The improved device comprises a support for the head of the tool from which the broken handle is to be removed and may be formed from a single section of heavy sheet metal or light plate metal of sufficient strength to withstand the strains to which it will be subjected, and bent into U-shape whereby spaced sides 10 and 11 and a base portion 12 are produced as shown in Figs. 1, 2 and 3, or with sides 13 and 14, corresponding to the sides 10 and 11, of the structure shown in Figs. 1, 2 and 3, of cast metal, preferably steel, as illustrated in Figs. 5 and 6.

The supporting device, whether in one or more pieces, is firmly attached to a relatively broad base 15, generally of wood.

When the sides 10 and 11 and base 12 are formed from a single piece as shown in Figs. 1, 2 and 3, a plurality of transverse slots 16 are formed through the sides 10 and 11, to receive bars 17 to support the tool head while the stump of the handle is being removed.

The slots will be located at different elevations to support different sized tool heads.

When the sides of the support are of cast metal as shown in Figs. 6 and 7, a plurality of upwardly and inwardly opening blind slots or seats 18 of varying lengths will be employed to hold the bars 17.

Attached to the portions 10 and 11 or 13 and 14, as the case may be, are upwardly arching combined guides and carriers 19 and 20, each preferably formed from a single section of metal bent into U-shape with the "leg" portions twisted one-fourth to bear flatly against the outer faces of the sides of the supports in position to receive the fastening bolts 21, but leaving the intermediate portions disposed vertically flatwise, as shown.

Disposed between the flatwise portions of the members 19 and 20 is a guide block 22 having transverse channels to receive the members 19 and 20, to enable the block to

be adjusted transversely in the space between the portions 10 and 11 or 13 and 14. A clamp screw 23 is tapped through one of the guide members, for instance the member 19, 5 to engage the block 22, and hold it in adjusted position.

The block 22 is formed with a longitudinal guideway 24 for a driving pin 25, conforming in transverse outline with the handle socket of the tool head from which the stump of the broken handle is to be removed. An adjusting screw 26 is tapped through 10 one of the sides to control the position of the tool head.

15 When the broken handle stump is to be removed from the eye of the head of an axe, indicated by dotted lines at 27 in Fig. 1, the bars 17 are located in position to hold the head and the adjusting screw 26 actuated 20 until it engages the head. By this means the head will be retained in position.

The drive pin is then inserted through the block 22 and the block adjusted on the members 19 and 20 until the pin is in position 25 above the stump and the block clamped in adjusted position by the clamp screw 23.

The pin is then driven against the stump by a hammer or other implement to loosen and remove the same.

30 If the broken end or stump of a hatchet, hammer, or like smaller tool is to be re-

moved, the bars 17 will be located in the upper slots 16 or in the shorter seats 18, as the case may be, and the smaller end of the driving pin inserted downwardly through the 35 block 22, as will be obvious.

The improved implement is simple in construction, can be inexpensively manufactured, and of any required material or capacity to receive tools of various sizes. 40

The preferred embodiment of the invention is disclosed in the drawings and set forth in the specification, but it will be understood that modifications within the scope of the claim may be made in the construction 45 without departing from the principle of the invention or sacrificing any of its advantages.

Having thus described the invention, what is claimed as new is:—

A tool handle removing device comprising spaced side members having supporting seats in their confronting faces, bars engageable in said seats and adapted to support a tool head, a holder supported on said side members and having a longitudinally directed guideway, and a striking pin movable through said guideway. 55

In testimony whereof, I affix my signature hereto.

WILLIAM D. SNOWMAN.
